[57] **ABSTRACT**

A watch case comprises a bezel frame to which a glass detachable only from the inside and a back cover are secured, and tamper-proof means comprising a small radial blind hole formed in said cover and engageable by means of a suitable tool, and a plug inserted to be engaged by a screw-threaded extraction rod, said plug being provided with a breakable cap covering said tapped hole and flush with the outer surface of the back cover.

TAMPER PROOF WATCH CASES

The present invention relates to watch cases in general and has specific reference to tamper-proof watch cases.

The trend towards the putting of increasingly expensive watch movements on the market, notably of quartz-type electronic movements, makes it necessary to provide means for preventing persons other than skilled repairers to have access to these movements. It is therefore necessary to enable these qualified repairers to positively ascertain whether or not a watch case has been previously opened by an unqualified and/or unauthorized person. It has already been established that the best solution for exerting this supervision consists in providing an element such that the case can not be opened unless this element is destroyed.

Thus, a known proposition consisted in utilizing a low-melting material cast on at least one portion of the place where the tool necessary for disassembling the component elements of the case must be inserted, so that the tool could not be inserted unless said material was removed, thus providing a tamper-proof seal enabling a repairer to check whether the case had previously been opened or not. However, even an unskilled person is capable of replacing this material, so that it becomes very difficult to ascertain whether the case was opened or not.

Another known solution applicable to a cup-shaped case bottom consists in assembling the cup-shaped bottom with the glass by means of a ring of relatively soft or ductile material which cannot be removed unless it is destroyed, the replacement of this ring requiring the use of a special tool. However, this solution is only applicable to a particular type of watch case with a shouleder glass insert. Furthermore, a false frame or bezel must be fitted to conceal the ring.

Under these conditions another solution applicable to watch cases with insert bottom or back cover, which meets the desired requirements, must be found, i.e. a device the disassembling of which necessarily involves its partial or complete destruction, and which can be manufactured only with great difficulty by persons other than skilled and qualified repairers.

According to the invention, there is provided a watch case comprising a main body portion and a cover removably fitted on the main body portion, a recess in said cover forming gripping means for cooperation with cover removal means, and a member removably blocking said recess to normally prevent cooperation thereof with removal means, said member comprising means which must be at least partially destroyed for removal of the member from the recess.

The accompanying drawings illustrate on considerably enlarged scales two typical embodiments of the invention. In the drawings:

FIG. 1 illustrates in fragmentary section a first embodiment;

FIG. 2 is a detail view of the composite plug utilized in the arrangement of FIG. 1, and

FIG. 3 illustrates a modified embodiment of the plug of FIG. 2.

The watch case illustrated in FIG. 1 comprises a bezel-frame 1 in which are retained, on the one hand, a glass 2 by means of an O-ring 3 engaging a pair of facing grooves 4, 5 formed in the bezel-frame 1 and glass 2

so as to interlock these members while sealing the joint therebetween and, on the other hand, an inner ring 1a. The glass 2 is formed with a bevel 6 for safely preventing the insertion of an extraction tool so that the glass cannot be removed unless a pressure is exerted on its inner surface. The case 1 is closed by a bottom cover 7 secured to the bezel-frame 1 in the same manner as the glass 2 by means of an O-ring 8.

10 However, this bottom cover 7 can be removed by pulling same outwards, but the only gripping means provided thereon consists of a hole 9 formed radially therein and normally closed by a plug 10 flush with the outer surface of this bottom cover 7, so that to remove this cover it is necessary firstly to free the hole 9 by extracting the plug 10.

15 The plug 10 shown on a larger scale in FIG. 2 comprises a metal body or piston 11 of a diameter slightly inferior to the diameter of said hole 9 and formed with an annular groove 12 in which an O-ring 13 is fitted; when compressed, this O-ring 13 will retain the plug 10 in its hole 9. The body 11 further comprises a tapped blind hole 14 in which a screw-threaded pull-out rod can be engaged when it is desired to extract the plug 10 20 from the hole 9. This tapped hole 14 is covered by a cap 15 for example of mineral glass sealed by cementing or melting on the metal body 11. Under these conditions, it is clear that no access can be had to the tapped hole 14 unless the glass-cap 15 is firstly broken. 25 Of course, this cap 15 may consist of any other suitable material, such as organic glass, synthetic glass or other plastic material.

30 To open the watch case the following procedure is adhered to: the cap 15 is firstly broken, and a rod (not shown) having a screw-threaded end corresponding to the tapped hole 14 is introduced into this hole, and the plug 10 is extracted together with the remaining fragments of the glass cap 15. Then, a stud-rod is inserted 35 and the portion thereof which emerges from the hole 9 constitutes a convenient gripping means for opening the bottom or back cover of the watch case. Upon completion of the repair or service work, the back cover is refitted in position and another capped plug is 40 force fitted into the hole 9. Since this plug is flush with the outer surface of back cover 7, it cannot be tampered with and removed without breaking the cap. 45

FIG. 3 illustrates a modified embodiment of the plug which consists of a cylindrical metal body 16 formed with a tapped extraction hole 17 covered by a cap 18 of 50 resilient synthetic material. The edge of this socket-shaped cap 18 comprises a shallow bead 19 having a diameter (when outside the hole 9) slightly greater than the diameter of this hole, so that when the plug is force-fitted into the hole 9 the bead 19 is compressed radially inwards. To permit the distortion of the edge of cap 18 the plug 16 is formed with a corresponding groove 20 into which the bead material is pushed when the cap 18 is fitted home, so that this cap becomes 55 locked to the plug 16 and cannot be pulled out therefrom. To remove the plug the cap 18 must be torn or stripped so that the necessary extraction rod (not shown) can be screwed into the tapped hole 17.

60 In order to avoid the manufacture of plugs by unauthorized persons, the cap and/or plug material is preferably of such nature that its origin can be ascertained by analysis. To this end, special alloys may be

used, or alternately reference substances or elements may be added to this material so that the presence or absence of these substances or elements, determined by appropriate methods, may reveal the authenticity or the falsity of the plug. Of course, the tamper-proof means described hereinabove is applicable not only to watch cases of the type illustrated but also to any watch cases having a separate bottom or back cover, whether this bottom or back cover is secured in the manner set forth hereinabove or inserted, screwed or secured by a bayonet system. Furthermore, the tamper-proof means of this invention may be carried out in practice with many modifications and variations without departing from the basic principles of the invention as set forth in the appended claims.

What is claimed is:

1. A watch case comprising a main body portion and a cover removably fitted on the main body portion, a blind hole in the outer surface of said cover forming gripping means for cooperation with cover removal means, a plug fitted in said blind hole to normally prevent cooperation thereof with removal means, and a cap of breakable material which is fitted on said plug and which must be at least partially destroyed for removal of the plug from the blind hole, at least a part of said cap being substantially flush with the outer surface of said cover.

2. A watch case as claimed in claim 1, in which said plug comprises a threaded hole accessible from outside said cover upon breaking said cap.

3. A watch case as claimed in claim 1, in which said plug comprises an annular groove, an O-ring being compressed in said annular groove by a wall of said blind hole to secure said plug in said hole.

4. A watch case as claimed in claim 1, in which said cap comprises material containing substances capable of being analyzed to ascertain the authenticity of the cap.

5. A watch case as claimed in claim 1, in which a glass is mounted in a bezel formed in said main body portion, said glass being fittable in and removable from said bezel of the main body portion solely by removal of said cover.

6. A watch case as claimed in claim 1, in which said plug comprises an annular groove, said cap being socket shaped and made in resilient material, at least a part of said cap being compressed in said annular groove by a wall of said blind hole to secure said plug in said hole.

7. A watch case as claimed in claim 6, in which a skirt-forming part of said cap comprises a shallow bead normally projecting from its outer surface.
